(57) **CLAIM**

The ornamental design for a stool, as shown and described.

DESCRIPTION

FIG. 1 is a top plan view for a stool showing my new design.

FIG. 2 is a front elevation view thereof.

FIG. 3 is a bottom plan view thereof.

FIG. 4 is a back elevation view thereof.

FIG. 5 is a left elevation view thereof.

FIG. 6 is a right elevation view thereof.

FIG. 7 is a top perspective view thereof; and,

FIG. 8 is a bottom perspective view thereof.

The broken line portion of the drawings is included to show portions of the stool that forms no part of the claimed design.
